UNITED STATES PATENT OFFICE.

GEORGE LEHNER, OF PITTSBURG, PENNSYLVANIA.

DESIGN FOR A DISPLAY-STAND FOR CLOCKS.

SPECIFICATION forming part of Design No. 32,979, dated July 24, 1900.

Application filed June 12, 1900. Serial No. 20,104. Term of patent 7 years.

To all whom it may concern:

Be it known that I, GEORGE LEHNER, a citizen of the United States of America, residing at Pittsburg, in the county of Allegheny and state of Pennsylvania, have invented and produced a certain new and useful Design for Display-Stands for Clocks, of which the following is a specification, reference being had therein to the accompanying drawings.

- o This invention relates to certain new and novel designs for display-stands for clocks, and has for its object to provide a design for a display-stand for clocks of new and original shape.
- 5 As shown in the accompanying drawings, the display-stand consists of the novel outline and configuration which will be hereinafter more fully described and specifically pointed out.
- o In describing the invention in detail, reference is had to the accompanying drawings, forming a part of this specification, wherein like numerals of reference indicate corresponding parts throughout both views, and in which—

Figure 1 is a perspective view of my new and novel design of display-stand for clocks. Fig. 2 is a side view thereof.

My design for display-stand for clocks is formed of a suitable piece of wire cylindrical in cross-section and bent to form a pair of vertically-extending sides 1, having the upper end thereof formed into a loop, as at 2, and terminating into an inclined top 3, having a centrally-arranged loop 4. The lower ends of the vertically-extending sides 1 are formed substantially diamond-shaped, as at 5. At the top of the diamond-shaped portions 5 the sides 1 are surrounded by a loop 6, which terminates into an outwardly-extending rectangular skeleton support 7, formed with a pair of loops 8.

Having thus fully described my invention, what I claim as new, and desire to secure by Letters Patent, is—

The design for a display-stand for clocks, substantially as herein shown and described.

In testimony whereof I affix my signature in the presence of two witnesses.

GEORGE LEHNER.
